LUE OSCAR BECK, OF BUFFALO, NEW YORK

DEVICE AND METHOD OF CLASSIFYING PATRONS

Application filed March 30, 1929. Serial No. 351,290.

This invention relates to a new device and method for classifying patrons of amusement houses, parks and resorts in which admission is charged to enter the enclosure forming the house or resort, and in which there may be additional subdivisions of amusements or other devices for the use of the patrons of the resort to which additional admissions are charged.

As patrons entering the various types of amusement resorts have different objects of entertainment in view or enter for some particular specific purpose, it is the object of this invention to segregate these patrons into different classes and to charge an admission upon entrance governed according to the amount of amusement or the special activity which each particular patron desires to follow, so that some patrons may be entered for admission fees more reasonable than others, thereby producing an inducement to all types and classes of people to utilize the facilities of the resort to the desired extent and whereby they will pay for only the amount of amusement or service received.

In carrying out this segregation and classifying of patrons in a resort, it is the object of this invention to distinguish these groups of patrons by issuing receipts for the admission price paid at the entrance to the resort or building, or other enclosure, and to permanently attach these receipts which are frangible, and may be mutilated, to the person of the patron in any suitable and desired manner, preferably by having the receipt in the form of an elongated, narrow strip of sheet material and applying this strip to the wrist of the patron so that it will encircle the wrist, and a suitable securing element which will permanently fasten the overlapping ends of the strip together to prevent removal of the strip from the wrist except by mutilation which will destroy the value of the receipt.

The invention further comprehends the provision of a frangible receipt strip for attachment to the human wrist so that it will encircle the wrist and have the ends extending laterally therefrom in overlapping rela-

tion, together with a permanent fastener for permanently attaching the ends of the strip in such a manner that it will be necessary to mutilate the strip and receipt when removing it from the wrist.

In the drawings forming part of this application;

Fig. 1 is a diagrammatic plan of an amusement hall, park, or other enclosure, illustrating the entrance and exit to the enclosure, together with additional entrances to segregated amusements within the enclosure to facilitate the explanation of the invention.

Fig. 2 is a perspective view illustrating the receipt strip applied to the wrist of a patron with a permanent fastener in such a manner that it must be mutilated in removal.

Fig. 3 is a plan view of the strip before it is applied to a patron.

Fig. 4 is a sectional view through the receipt strip showing how the permanent fastener attaches the overlapping ends of the strip together.

In Fig. 1, the numeral 1 indicates the outer walls of a building which may for example be a dance hall, although any type of amusement building, park or enclosure may be used in carrying out the invention. The entrance to the dance hall is indicated at 2 which has the usual ticket booth 3 adjacent thereto. Patrons entering the dance hall may selectively purchase and obtain several types of tickets including a special admittance receipt hereinafter more fully discussed. An important feature of the invention is the form of the admittance receipt which consists of a strip of paper, celluloid, or other frangible material indicated at 4 which is applied so as to encircle the wrist of the patron as illustrated in Fig. 2.

After this strip is placed about the wrist in a manner illustrated in Fig. 2, a suitable wire stapling machine or other type of permanent fastening device will be applied to the overlapping ends 5 of this strip and operated to apply the wire fastener 6 to these overlapping ends in order to permanently connect them together. This connection will be made in such a manner that the strip 4

forming the receipt for the admission price paid in the booth 3 will be permanently attached to the wrist and can not be removed over the hand without tearing, breaking or 5 otherwise mutilating the material of the strip. Then the patron is free to enter and use the facilities of the dance hall according to the particular plan observed. These strips 10 4 will be made in different colors for different groups of patrons paying different admission fees and different colors will also be used on successive days in order that the patrons on one day will be unable to use the receipts on succeeding days. Any other suitable 15 method of segregating the strips into groups by suitable indicia or other designating characters may be used in place of colors and all of these methods of identification of the receipts are comprehended by the invention. 20

In the operation of a dance hall, for example, a certain group of patrons do not desire to dance but prefer to enjoy the music and watch others dance, in which case they 25 frequently object to paying the admission fee which is required of those who desire to dance and use the full facilities of the hall. As a result, this invention provides a means whereby visitors and others who do not dance 30 may enjoy the entertainment by purchasing an admission at a special price considerably less than those who dance will be required to pay. Should these patrons after entering 35 desire to dance, then they may procure tickets for any particular dance hall at the booth 7 within the dance hall 1 which will admit them to the dance floor 8 within the railing or other type of partition 9 used to divide the 40 dance floor from other portions of the hall indicated at 10 to which the patrons are admitted. Then, those patrons who have secured admission at the reduced price will 45 pay for each dance through the purchase of tickets or other suitable arrangement and as they enter onto the dance floor through the 50 gate 11 will hand their tickets to the attendant stationed at 12.

With the class of patrons who desire to 55 dance frequently, it is necessary to secure a much greater admission fee and is therefore expedient to fully encourage and convenience such patronage. To properly satisfy this class of patrons, they will upon payment of a special admission fee at the booth 3 be supplied with identifying receipts of a special color which are attached to the wrist in the manner disclosed in Fig. 2. When these 60 patrons desire to dance, they may obtain entrance through the gate 11 merely by exhibiting their receipts to the attendant of the 65 dance hall stationed at 12. Thus these patrons upon exhibiting their bands will not be required to go to the difficulty and inconvenience of paying a special fee for enjoying each successive dance.

When the patron leaves the dance hall, he will obviously desire to remove his receipt and in order to do so, it will be necessary to tear or otherwise mutilate the receipt in order to sever the connection, and as a result, it will not be useful on another occasion. 70

This receipt issued to the patron upon admission may be obviously applied to the clothing of the patron or in any other manner 75 so long as it is required to be mutilated when removed.

It is to be understood that this method of operating an amusement hall may be applied in theaters, amusement parks and other places 80 where it is found desirable to provide for several classes of patrons paying different admission fees by attaching the patron's receipt for his admission to his person in any suitable manner so that after removal, the 85 receipt is necessarily mutilated when it loses its value for further admission to the amusement within the hall, theater or other enclosure, and that the invention herein disclosed clearly comprehends the classifying 90 of patrons into groups regardless of the nature of the entertainment or amusement or other business to which the invention may be applied. 95

What is claimed is:

1. As an article of manufacture, a strip 95 of light frangible sheet material forming an admission receipt, said strip having a length sufficient to encircle the human wrist and provide overlapping end portions, and a permanent metallic fastener having portions extending through and joining said overlapping ends to prevent removal of said strip from the wrist except by mutilation thereby 100 destroying the receipt. 105

2. A method of attaching a visible receipt strip to the wrist for the purpose described, consisting of wrapping a frangible strip of material about the wrist with the ends thereof in abutting relation, then inserting 110 said ends in a stapling device, and finally stapling the ends together therein. 115
